CLAIM

The ornamental design for a modular building, as shown and described.

DESCRIPTION

FIG. 1 is a perspective view of a modular building showing my new design.

FIG. 2 is a front view of the modular building of FIG. 1.

FIG. 3 is a rear view of the modular building of FIG. 1.

FIG. 4 is a left side view of the modular building of FIG. 1.

FIG. 5 is a right side view of the modular building of FIG. 1.

FIG. 6 is a top view of the modular building of FIG. 1; and,

FIG. 7 is a bottom view of the modular building of FIG. 1.

The broken lines shown herein are for illustrative purposes and form no part of the claimed design.

1 Claim, 7 Drawing Sheets---
